[57] **CLAIM**

The ornamental design for a portable two-way radio or similar article, substantially as shown and described.

DESCRIPTION

FIG. 1 is a front, top and left side perspective view of a portable two-way radio or similar article showing our new design, with the antenna shown as broken for convenience of illustration;

FIG. 2 is a right side elevational view thereof; and

FIG. 3 is a rear elevational view thereof; and

FIG. 4 is a view like FIG. 1 of a modified form of the radio, wherein the wrap-around front and left side and the oblong bottom right side panels are both textured and the top antenna and controls are of different configurations.
